UNITED STATES PATENT OFFICE.

JULIUS KAHN, OF DETROIT, MICHIGAN, ASSIGNOR TO TRUSSSED CONCRETE STEEL COMPANY, OF DETROIT, MICHIGAN, A CORPORATION OF MICHIGAN.

PROCESS FOR FORMING RIBBED EXPANDED METAL.

948,417.

Specification of Letters Patent. Patented Dec. 14, 1909.
Application filed April 5, 1909. Serial No. 488,103.

To all whom it may concern:

Be it known that I, JULIUS KAHN, a citizen of the United States, and a resident of Detroit, in the county of Wayne and State of Michigan, have invented a new and Improved Process for Forming Ribbed Expanded Metal, of which the following is a specification.

This invention relates to the manufacture of that type of expanded metal disclosed in Patent No. 862,897 to Forsyth, dated August 13th, 1907, and is a modification of the process described in Patent No. 920,152, dated May 4th, 1909, to Kane.

The object of my improved process is to produce a ribbed expanded metal wherein the ribs of any desired size may be spaced considerable distances apart.

In the process described in the Kane patent, the size of the ribs is in fixed proportion to the amount of the reticulated metal between the ribs is expanded. It is often desirable that the ribs be of such size that to form them on the metal sheet in the manner explained in said patent would be ineffectual to properly expand the metal.

In the accompanying drawing, Figure 1 is a plan of a portion of a sheet of metal properly slotted previous to expanding. Fig. 2 is a plan of the sheet after the tongues that formed the connecting ties have been pressed down. Fig. 3 is a cross section on the line 3—3 of Fig. 2. Fig. 4 is a cross section on the line 4—4 of Fig. 2, both Figs. 3 and 4 being on a slightly larger scale than the others. Fig. 5 is a cross section on the same line as Fig. 3 after the first expansion. Fig. 6 is a similar cross section after the second expansion. Fig. 7 is a plan of a sheet after such second expansion.

Similar reference characters refer to like parts throughout the several views.

As in the Forsyth patent, expanded metal is formed by slitting a sheet 1 along longitudinal lines. The transverse slits 2 connect to the ends of longitudinal slits 3 and 4, the slits 3 extending between the slits 4 as shown in Fig. 1. Blank portions 5 are left between the bands of slotted metal. The slotted metal is next passed through the forming press and the tongues 6 are pressed down, the sheet then being in the form shown in Figs. 2 and 3. At the same time, small grooves 7 are formed in the blank portions 5 of the sheet.

In the process described in the Kane patent, the sheet is next passed through the grooving dies, whereby the sheet is expanded. It has been found that it is often impossible to obtain the maximum amount of expansion for a given number and size of ribs by the Kane process. To obtain this maximum expansion, the outer edges of the sheet shown in Figs. 2, 3 and 4 are drawn apart, causing the tongues 6 to open as shown in Fig. 5. The partly expanded sheet is then passed through the ribbing dies, as described in the Kane patent, resulting in the ribs 10, shown in cross section in Fig. 6. The sheet receives its final expansion by these dies, and the amount that each reticulated band is expanded is equal to the difference between the distance between the points 8 and 9, around the rib 10, and straight across.

The difference in the resulting expansion of the sheets according to the Kane process and according to the process above set forth is that given to the sheet before the ribs are formed. By using the Kane process, a sheet having the same area for the same weight could be formed, but the ribs would be spaced close together and would be smaller. This present process permits of fewer ribs for the same area of expanded metal. It also gives greater area of expanded metal for the same weight, with but slightly less strength.

Having now explained my improved process, what I claim as my invention and desire to secure by Letters Patent is:—

1. The process of forming ribbed expanded metal, consisting in slitting the same to form parallel bands of slotted portions separated by parallel grooved bands of entire portions, the slitting being along longitudinal lines so as to form tongues split through their bases; then striking up the tongues so that the main portions will extend at practically right angles to the sheet, the ends being parallel to the sheet; then separating adjacent entire portions to cause the tongues to open; and then passing the sheets through grooving dies to form the entire portions into U-shaped ribs, at the same time preventing the sheet from contracting generally, whereby the expanding of the slotted bands is completed.

2. The process of forming ribbed expanded metal which consists in forming a sheet

with longitudinal series of slits and bands of entire metal alternately, then separating the bands of entire metal to laterally expand the slitted portions, and then forcing all the bands of entire metal into the grooves of a die simultaneously, thereby completing the expansion of the slitted portions.

3. The process of forming expanded sheet metal reinforced by longitudinal ribs extending from one face of the same, which consists in first slitting the sheet so as to form parallel bands of slitted metal separated by bands of entire metal, then striking up portions of the slitted metal to form parallel rows of split tongues and forming small grooves down the middle line of the bands of entire metal, then laterally sepa-

rating the bands of entire metal thereby opening the tongues, and then placing the sheet between dies having grooves and projecting tongues in such a manner that a tongue on the dies will enter each groove in the entire portion of the sheet, and operating the dies to form ribs, the drawing in of the edges of the entire portions of the sheet completing the expansion of the slitted portions.

In testimony whereof I have signed this specification in the presence of two subscribing witnesses.

JULIUS KAHN.
